UNITED STATES PATENT OFFICE.

WILLIAM E. COUNTER AND LEE O. MILLER, OF THREE RIVERS, MICHIGAN.

SCREW-HOLDER FOR WATCH-REPAIRERS.

SPECIFICATION forming part of Letters Patent No. 392,589, dated November 13, 1888.

Application filed April 26, 1888. Serial No. 271,921. (No model.)

To all whom it may concern:

Be it known that we, WILLIAM E. COUNTER and LEE O. MILLER, citizens of the United States, residing at Three Rivers, in the county 5 of St. Joseph and State of Michigan, have invented certain new and useful Improvements in Screw-Holders for Watch-Repairing, of which the following is a specification, reference being had therein to the accompanying 10 drawings.

This invention relates to new and useful improvements in the screw-holders for watch-repairing, and the object of the invention is to form a device for the use of watch-repairers 15 which may be conveniently used on the bench, whereby the movement-screws taken out in taking the watch apart to clean or repair will not become lost or mixed.

It is well known that in repairing watches 20 all careful workmen endeavor to put the screws back in the same screw-hole from which they are taken out, and where the screws are placed in a common receptacle this is practically impossible. To this end our device is 25 designed to keep the screws apart and set them in such places that their identity is always preserved, and they are kept from becoming mixed or lost.

Our invention consists in making the screw- 30 holder reversible, whereby the device may be used for watches of different designs, one side preferably being provided with the typical design of American watches and the other side with the typical design of foreign watches, all 35 as more fully hereinafter described.

In the drawings which accompany this specification, Figure 1 is a perspective view of our improved screw-holder. Fig. 2 is a plan of the reverse side thereof; and Fig. 3 is a vertical 40 central cross-section.

A represents a plate preferably of circular shape and provided with the raised edge B.

C are outlines or identification-marks of the parts of the works of the watch-movement as 45 it appears on the reverse side, and D are holes placed in such relation to the outlines as to identify the position of the screws in each particular part of the work. The holes are of

such size as to readily allow the threaded portion of the screw to be inserted therein and 50 hold it suspended by its head.

E are legs supporting the plate A, and A' is a similar plate to the plate A and similarly arranged, except that it is preferably marked with the design of a different watch-move- 55 ment, so that the device may be reversed to be used either side.

In practice we prefer to provide one of the plates with the typical design of the American watch-movements, and the other plate with 60 the typical design of the foreign movements; but, if desired, a multiplicity of such tables may be connected together into one device embracing different designs of watch-movements; or but one plate alone with suitable 65 legs may be used where no necessity exists for the use of more than one design.

The device may be cheaply manufactured of sheet metal and its use will be found of value in watch-repairing, saving time and be- 70 ing conducive to good repairing.

What we claim as our invention is—

1. As an improved article of manufacture, a reversible screw-holding device consisting of two plates, one upon each side of the de- 75 vice and each provided with holes D and indica- 80 tion marks or designs of watch-movements, those on one plate representing different movements from those on the other plate, substantially as described.

2. As a new article of manufacture, the herein-described sheet-metal screw-holding device, consisting of the plates A A', provided with raised edges, the legs E, connecting them reversely together, the holes D in the plates, 85 and the identification marks or designs of different watch-movements upon the plates A A', substantially as described.

In testimony whereof we affix our signatures, in presence of two witnesses, this 12th day of 90 April, 1888.

WILLIAM E. COUNTER.
LEE O. MILLER.
